UNITED STATES PATENT OFFICE

93,351

DESIGN FOR A BOTTLE OR SIMILAR CONTAINER

Harry R. McDonald, Dunkirk, Ind., assignor to Hart Glass Manufacturing Company, Dunkirk,
Ind., a corporation of Indiana

Application July 11, 1934, Serial No. 52,535

Term of patent 14 years

To all whom it may concern:

Be it known that I, HARRY R. McDONALD, a citizen of the United States, residing at Dunkirk, Jay County, Indiana, have invented a new, original, and ornamental Design for a Bottle or Similar Container, of which the following is a specification, reference being had to the accompanying drawing, forming part thereof.

Fig. 1 is a front elevation of a bottle or similar container embodying my new design; Fig. 2 is a central vertical section; Fig. 3 is a rear elevation; and Fig. 4 is a top plan view.

I claim:

The ornamental design for a bottle or similar container, as shown.

In witness whereof, I have hereunto set my hand.

HARRY R. McDONALD.
